UNITED STATES PATENT OFFICE.

DAVID C. NOGGINS, OF NEW HAVEN, CONNECTICUT.

DESIGN FOR A COMBINED TABLE AND LAMP.

Application filed January 7, 1928. Serial No. 24,777. Term of patent 14 years.

To all whom it may concern:

Be it known that I, DAVID C. NOGGINS, a citizen of the United States, residing at New Haven, in the county of New Haven and State of Connecticut, have invented a new, original, and ornamental Design for a Combined Table and Lamp, of which the following is a specification, reference being had to the accompanying drawing, forming part thereof.

Fig. 1 is a side view of a combined table and lamp showing my new design; and
Fig. 2 is a top view of the same.

I claim:

The ornamental design for a combined table and lamp as shown.

DAVID C. NOGGINS.
